US0D1022465S

(12) **United States Design Patent** (10) **Patent No.:** **US D1,022,465 S**
(45) **Date of Patent:** **** Apr. 16, 2024**

(54) **CONTAINER**

(71) Applicant: **ShenZhen YiHong Technology Co., LTD**, Guangdong (CN)

(72) Inventor: **Yi Dai**, ShenZhen (CN)

(73) Assignee: **ShenZhen YiHong Technology CO., LTD**, ShenZhen (CN)

(**) Term: **15 Years**

(21) Appl. No.: **29/906,459**

(22) Filed: **Nov. 5, 2023**

(51) **LOC (14) Cl.** **09-04**

(52) **U.S. Cl.**

USPC **D3/304; D3/307**

(58) **Field of Classification Search**

CLAIM

The ornamental design for a container, as shown and described.

DESCRIPTION

FIG. 1 is a perspective view from above of a first embodiment of a container showing my new design;

FIG. 2 is a perspective bottom view thereof;

FIG. 3 is a left side view thereof;

FIG. 4 is a right side view thereof;

FIG. 5 is a front view thereof;

FIG. 6 is a back view thereof;

FIG. 7 is a top view thereof;

FIG. 8 is a bottom view thereof;

FIG. 9 is a perspective view of the container in use; and, FIG. 10 is a perspective view of a second embodiment of the container, shown with a transparent surface finish.

The dash-dash broken lines showing a container lid depicts environmental subject matter that forms no part of the claimed design.

1 Claim, 7 Drawing Sheets
